CLOTH WINDING APPARATUS

Pleasant G. Moore, Granite Falls, N. C.

Application June 5, 1946, Serial No. 674,460

2 Claims. (CL 242—62)

1

This invention relates to a machine for winding cloth from a roll onto a tube and is especially designed for use in stores for dispensing small pieces of cloth of a few yards to customers by winding from a large roll onto a tube and the like, so that the cloth is wound and measured and delivered to the customer in a compact roll, thus avoiding wrinkling and breaking of the cloth, such as in the case of oil cloth and the like.

It is an object of this invention to provide a cloth winding and measuring machine, which is adapted to hold a roll of cloth, and having means for clamping the end of the piece of cloth and unwinding it from the roll and winding it into a smaller package for delivery to customers.

It is another object of this invention to provide in a cloth winding machine, means supporting for rotation a roll of cloth, and means for supporting a tube onto which the cloth is wound, with means at each end of the tube for clamping the edges of the cloth, so that it will be wound around the tube, as the tube is rotated by suitable means associated with the tube.

It is also an object of this invention to have the apparatus adjustable for various widths of cloth.

Some of the objects of the invention having been stated, other objects will appear as the description proceeds, when taken in connection with the accompanying drawings, in which:

Figure 1 is a top plan view of the apparatus with portions thereof broken away;

Figure 2 is a front elevation of the apparatus with portions broken away;

Figure 3 is a vertical sectional view taken along the line 3—3 in Figure 2;

Figure 4 is a transverse sectional view taken along the line 4—4 in Figure 1;

Figure 5 is a vertical sectional view taken substantially along the line 5—5 in Figure 1;

Figure 6 is a vertical sectional view taken along the line 6—6 in Figure 5;

Figure 7 is a transverse sectional view taken along the line 7—7 in Figure 6, and showing the cloth clamped in position;

Figure 8 is a vertical sectional view taken along the line 8—8 in Figure 2.

Referring more specifically to the drawings, the numerals 10 and 11 indicate the front and rear foundation strips of the apparatus, and the end foundation strips are indicated at 12. Onto these foundation strips or framework is secured a suitable board 13 on which the main portion of the apparatus is mounted. The device is provided with a rear wall 14 and end walls 15 and 16.

2

On top of the bottom board 13 and on the front edge of the rear wall 14 is mounted a plurality of upstanding members, such as 20, 21, 22 and 23, and these are cut away into a substantial semi-circle, and mounted between the upright members 20 and 21 is a plurality of rollers 25 and between the members 22 and 23, is mounted a plurality of rollers 26, on which a roll of cloth 27 is adapted to be supported.

On the front upper portion of the uprights 20 to 23 inclusive, there is mounted a bar 30. On the bar 30, there is mounted a plurality of inverted U-shaped members 31, having suitable bearings 32 confined therein, and in these bearings 32, the ends of rollers 33 and 34 are mounted. On a portion of one of the end walls, such as 16, is a suitable cloth measuring apparatus, the shank of which is indicated at 35, and this has a casing 36, in which suitable measuring apparatus is disposed and this casing 36 has a slot 37, through which the cloth 27a from roll 27 is passed, where it engages rollers 40 and 41 to actuate the measuring apparatus, which is closed beneath a dial 43, but not shown. The support 35 is secured to an uprising board 38, which rises from the base board 13.

Secured to the cloth measuring shank 35, is a bracket 45 and suitable brackets 46 and 47 are also secured to the upper front edges of members 20 to 23 inclusive, and project forwardly and have a closed channel member 48 secured on the front portions thereof, which confines a slotted bar 49, having a slot 50 extending from one end thereof to the other. Forwardly of the forward edges of the end boards 15 and 16 are secured the strips 51 and 52, on which are mounted flat members 53 and 54, these being secured to flat members 51 and 52 by means of suitable bolts 55. These members 53 and 54 extend substantially from one side of the machine to the other.

Slidably mounted on members 51 and 52 and confined by the undercut members 53 and 54 is a pair of slides 60 and 61, which are adjusted apart from each other by means of a plurality of bolts 62 having their head members embedded in one of the members 60 or 61, and having their threaded ends projecting into suitable holes in the other of these members, so that they can be spread apart from each other to give the proper amount of bind or friction between members 60 and 61 and members 53 and 54.

Mounted on these members 60 and 61 is a plate 63, which is secured to members 60 and 61 by means of suitable bolts 64, and mounted on the plate 63 is a member 66, on which rests a

U-shaped bracket having a base 67 and uprising spaced apart prongs 68 and 69, the base portion 67 being secured to plate 63 by means of suitable bolts 70 and 71. Rotatably mounted in these uprising members 68 and 69 is a shaft 72 having fixedly secured thereon a pinion 74, which meshes with a pinion 75 which is fixedly mounted on a shaft 76 which is rotatably mounted in the upper end of members 68 and 69. The shaft 76 projects inwardly from the end of the machine and has a rounded portion 77, onto which is adapted to fit one end of a tube 78, onto which cloth is adapted to be wound.

Fixedly secured on the shaft 76 is a wheel 85 having a counter-weight portion 79 and about 180° from portion 79 is a projecting portion 80. The wheels 85 and 85' are secured in their respective shafts 76 and 76' by any suitable means, such as a set screw 85a. The shaft 76 is recessed, as at 81, and in this recess portion is movably mounted a plug 82, which has a projecting arcuate portion 83 and the shaft 73 is cut away, as at 84.

The wheel 85 has a slot 86 therein which coincides with the cut away portions 81 in shaft 76 and in the cut away portion 81 and slot 86 is slidably mounted a block 87, which is integral with arcuate portions 83. Fixedly secured in block 87 by means of a set screw 88 is a shaft 89, which slidably penetrates portion 80, and has confined between portion 80 and block 87 a compression spring 90.

The upper end of shaft 89 has a head 91 thereon and immediately below the head is a sleeve 92 and immediately below the sleeve 92 is a button 93 which is rotatably mounted on shaft 89. This button has a beveled lower surface 94, so that when the button is turned 90° from the position, shown in Figures 5 and 6, this cam surface 94 of riding on a cam surface 95 on the portion 80 of the wheel will raise the block 87 and its arcuate portion 83 upwardly to allow the edge of a piece of cloth to be inserted between the cut away portion or cavity 84 and the arcuate portion 83, and then when the button 93 is turned back to the position, shown in Figures 5 and 6, and will clamp the edge of the cloth in position ready to be wound around the tube 78.

Slidably mounted between the other ends of members 53 and 54 and resting on members 51 and 52 is a pair of members 96 and 97, which are identical as to shape to members 60 and 61. These members are spread apart by bolts 98 which are identical to bolts 62 for the right hand side of the machine as used in Figures 1 and 2. Mounted on these members 96 and 97 is a plate 100, which is secured to the members 96 and 97 by means of suitable bolts 101 and on this plate 100 is mounted a base member 102, which is secured to the base member 100 by suitable bolts 103. This base member 102 has rising upwardly therefrom spaced uprights 104 and 105, in which is rotatably mounted a shaft 106, which has a crank 107 thereon for imparting rotation to the shaft. On this shaft 106 is mounted a pinion 74'. Meshing with this pinion 74' is another pinion 75' which is mounted on a shaft 76', and on this shaft 76' is mounted duplicates of the structure associated with shaft 76, and a description is not deemed necessary because the same reference characters will apply with the prime notation added.

In order to move the left hand assembly in Figure 1, comprising plate 100 and associated parts, away from and towards the right hand assembly mounted on plate 63 so as to insert

the tube 78 in position and to remove the tube with the cloth wound thereon, there is provided a bracket 108, in which is pivotally mounted, as at 109, a lever 110 which has pivotally connected thereto, as at 111, a link 112 which is pivotally secured to plate 100, as at 113. By swinging the lever 110 on its pivot 109, the plate 100 and the assembly carried thereby can be moved relative to the guide-way rails 53 and 54 to remove or install a tube 78 on the projections 77 and 77'.

Mounted on the slides 60 and 61 by any suitable means, such as bolts 116, is a plate 115 and on this plate 115 is mounted a bracket 117, by means of bolts 118, and projecting upwardly from this bracket is a board 120, which has integral therewith a clamp 121, which by means of a bolt 122 clampingly supports a bearing 123, in which is rotatably mounted a tube 124, fixedly secured on shaft 72 at one end, and supported by the bearing assembly 123 at the other end. This tube has a pin or key 127 integral therewith, which projects into a keyway 128 extending along the shaft 106, so that regardless of the adjustment of the plates 63 and 100 apart from or towards each other, the turning of shaft 106 will at all times rotate shaft 72, and thus both pinions 74 and 74' will be rotated in unison.

It is thus seen that I have provided a convenient apparatus for holding a roll of cloth, and for winding any desired number of yards from the roll onto the tube, wherein the roll of cloth of any desired length can be supported on the rollers 25 and 26 and can be led over the elongated rollers 34 across the slot 50 and clamped beneath the arcuate portions 83 and 83' and when the desired number of yards are wound a knife can be passed along slot 50 to cut the cloth at the proper place.

It might be added that the sleeve 92 has a bore of sufficient size to accommodate a compression spring 92a which tends to hold the member 93 down against cam surface 95 even when the parts are in the clamping position shown in Figures 5 and 6.

In the drawings and specification, there has been set forth a preferred embodiment of the invention, and although specific terms are employed, they are used in a generic and descriptive sense only, and not for purposes of limitation, the scope of the invention being defined in the claims.

I claim:

1. Cloth winding apparatus comprising a frame, a compartment disposed transversely of the rear end of the frame and having a plurality of substantially semicircular members mounted transversely thereof and each provided with rollers for rotatably supporting a roll of cloth, a slotted member across which the cloth passes so that a knife can be inserted through the cloth and drawn transversely through the cloth and guided by said slotted member for severing the cloth, a transversely disposed double trackway disposed across the front of the frame and having a pair of slidable members for movement therealong, each slidable member having an uprising bracket, a telescopic shaft mounted in the uprising brackets and having a pinion secured on each end thereof, a pair of stub shafts disposed in the upper end of the uprising brackets and each having a pinion thereon engaging with the pinions on the telescopic shaft, the said stub shafts each having clamping members mounted thereon for clamping the edges of the cloth, the proximate

ends of the stub shafts being pointed and having a shoulder against which the ends of a tube onto which cloth is adapted to be wound are adapted to fit when the two slides are moved toward each other, each of the clamping members comprising a radially slidable member having a clamping bill projecting inwardly toward the proximate ends of the stub shafts, resilient means for normally moving the radially slidable members into engagement with the stub shafts, each of the clamping members having means for moving the radially slidable members radially of the clamping members, the slides being mounted on said trackways for movement toward and away from each other, means for adjustably securing one of the slides in position near one end of the trackway and a lever pivoted at one end to one of the trackways and having a link pivoted intermediate its ends and the other end of the link being pivoted to the other slide, whereby said other slide can be quickly moved longitudinally of the trackway for moving the shoulder on the stub shaft associated therewith toward and away from one end of a tube disposed between the proximate ends of the stub shafts.

2. In a cloth winding apparatus comprising a frame, a transversely disposed compartment at one end of the frame having arcuate members disposed thereacross and provided with rollers for supporting a roll of cloth from which the cloth is to be unwound, means for winding the cloth from the cloth roll, comprising a pair of transversely disposed trackways, a slide mounted near each end of the trackway, a pair of brackets rising from said slides and having the ends of a telescopic shaft mounted therein, each end of the telescopic shaft having a pinion fixed thereon, a stub shaft mounted in the upper ends of said brackets and having pointed proximate ends and having a shoulder portion spaced from the proximate ends, each of the stub

shafts having a pinion mounted thereon for engagement with the pinions on the telescopic shaft, each of the stub shafts having fixedly mounted thereon a substantially circular housing, a radially movable member disposed in each housing and having an inwardly projecting tongue arcuate in cross section adapted to project inwardly toward the shoulder portion on the proximate ends of the stub shafts for engaging the edges of a piece of cloth, the shoulders on the proximate ends of the stub shafts being adapted to fit against a tube disposed therebetween and onto which the cloth is adapted to be wound, resilient means for normally pressing the radially movable members inwardly to cause their tongues to engage the stub shafts to clamp the edges of the cloth to the stub shafts, one of said slides being adjustable along the trackway to any desired position and the other of said slides being slidable along the trackway, means for quickly moving the other of said slides toward and away from the first slide, comprising a lever pivoted at one end to a fixed portion of the frame and having a link pivoted at one end intermediate the ends of the lever and having its other end pivoted to the said other slide and whereby the said other slide can be quickly moved away from and toward the first slide to thereby quickly remove or install a tube between the proximate ends of the two stub shafts.

PLEASANT G. MOORE.
